Attg.

United States Patent Office.

JOHN C. GOVE, OF CLEVELAND, OHIO.

Letters Patent No. 87,486, dated March 2, 1869.

IMPROVED STREET-CAR DRAW-BAR.

The Schedule referred to in these Letters Patent and making part of the same.

To all whom it may concern:

Be it known that I, JOHN C. GOVE, of Cleveland, in the county of Cuyahoga, and in the State of Ohio, have invented certain new and useful Improvements in Street-Cars; and do hereby declare that the following is a full, clear, and exact description thereof, reference being had to the accompanying drawings, and to the letters of reference marked thereon.

The nature of my invention consists in the application of two rubber springs to the draw-irons of a street-car, which will protect both the horses and car from injury resulting from a sudden start or stoppage.

In order to enable others skilled in the art to which my invention appertains, to make and use the same, I will now proceed to describe its construction and operation, referring to the annexed drawings, which form a part of this specification, and in which—

Figure 1 is a bottom view of the platform of a car, showing my invention applied to the same, and

Figure 2 is a side view, in section, of the front end.

A represents the platform of a street-car, and

B is the beam forming the sill of the car.

On the under side of said platform, a suitable distance from the centre, and on each side thereof, is a cross-bar, C, extending the whole width of the platform.

Between these bars C C is placed a frame, D, which projects in front of the platform, forming there a rounded bumper, as shown in the drawings.

This frame is held up in proper position by one or more bars, E, secured to the cross-bars C C; and near the front ends of the same is placed a roller, F, to facilitate the motion of said frame forward and backward.

The roller F is placed in journal boxes on the lower side of the bars C C, and the front end of the frame D rests on it, being, at that end, provided with metal plates, G G, to prevent the wearing of the same.

The draw-iron H passes through the frame D, and through the sill B, as shown in fig. 1.

On said draw-iron are placed two rubber springs, I I, one between the rear end of the frame D and the sill B, and the other in rear of said sill, the draw-iron being secured by means of a washer, a, and pin, b, as seen in fig. 1.

It will now be seen that, when the horses start the car, the tongue being secured to the front end of the draw-iron H, there will not be that dead pull, as is usually the case, for the rear spring, I, will first be acted upon before the car is operated upon.

In like manner, when the car is backed or taken into the car-house, and strikes against anything, the front spring will protect it from injury that else would be occasioned by the too sudden shock.

The frame D is, at the front end, where it forms, as described, the rounded bumper, covered with a metal plate, e, which also extends, on top, backward, projecting above and over the front edge of the platform A, protecting the frame and draw-iron from dirt, &c.

I am aware that the draw-heads of steam railroad-cars have been provided with rubber on their ends heretofore.

My invention is intended especially for cars drawn by horses, to facilitate the starting of the same.

What I claim, is—

The arrangement of the sliding frame D, rounded at its forward end, roller F, draw-iron H, rubber springs I I, and washer a, with the platform A and sill B of a street-car, substantially as and for the purposes herein set forth.

In testimony that I claim the foregoing, I have hereunto set my hand, this 12th day of September, 1868.

Witnesses:

JOHN C. GOVE.

WILLIAM THOMPSON,

H. X. HARTZ.
